United States Patent Office

Des. 183,635

Patented Sept. 30, 1958

183,635

TRACING IMPLEMENT

Norman Thomas Sanders, Studley, England, assignor to
Needle Industries Limited, Birmingham, England, a
British company

Application June 18, 1957, Serial No. 46,638

Claims priority, application Great Britain
February 6, 1957

Term of patent 3½ years

(Cl. D3—19)

FIG. 1

FIG. 2

FIG. 4

FIG. 5

Figure 1 is a side elevational view of a tracing implement showing my new design;

Figure 2 is a top plan view thereof;

Figure 3 is an end elevational view as seen from the left of Figure 1;

Figure 4 is a perspective view showing the side opposite to Figure 1; and

Figure 5 is a side elevational view thereof as it appears in closed position.

I claim:

The ornamental design for a tracing implement, substantially as shown.
